UNITED STATES PATENT OFFICE

EUGENE L. WEAVER, OF LOS ANGELES, CALIFORNIA, ASSIGNOR TO HARRY B. CARPENTER, OF LOS ANGELES, CALIFORNIA

DESIGN FOR A SELLING BOOTH

Application filed October 2, 1930. Serial No. 37,106. Term of patent 3½ years.

To all whom it may concern:

Be it known that I, EUGENE L. WEAVER, a citizen of the United States, residing at Los Angeles, in the county of Los Angeles and State of California, have invented a new, original, and ornamental Design for Selling Booth, of which the following is a specification, reference being had to the accompanying drawing, forming part thereof.

Fig. 1 is a top plan view of a selling booth showing my new design.

Fig. 2 is a front view in side elevation of the same.

I claim:

The ornamental design for a selling booth, as shown.

EUGENE L. WEAVER.
